UNITED STATES PATENT OFFICE.

CLARENCE L. MORTON, OF RAVENNA, OHIO, ASSIGNOR OF ONE-HALF TO WILLIAM
PETERS, OF RAVENNA, OHIO.

WASHING MACHINE.

Application filed March 7, 1922. Serial No. 541,650.

To all whom it may concern:

Be it known that CLARENCE L. MORTON, a citizen of the United States of America, residing at Ravenna, in the county of Portage and State of Ohio, has invented new and useful Improvements in Washing Machines, of which the following is a specification.

10 The object of the invention is to provide a
washing machine wherein the water con-
taining any suitable detergent or cleansing
preparation may be forced to penetrate the
fabrics subjected to the action of the ma-
chine by the force of suction induced by
15 plungers actuatable under conditions serving
to minimize the exertion of the operator and
avoid the unnecessary strain upon or rub-
bing of the fabrics with a view to minimiz-
ing the tendency to injure even those fabrics
20 which are of a relatively delicate texture;
and with these objects in view the invention
consists in a construction and combination
of parts of which a preferred embodiment is
shown in the accompanying drawings,
25 wherein:—

Figure 1 is a longitudinal vertical sectional view of the machine constructed in accordance with the invention.

Figure 2 is a detail sectional view showing the mounting of the operating lever.

Figure 3 is a plan view of the rack.

The machine consists essentially of a receptacle 10 which in the construction illustrated is of rectangular form with a removable cover 11 carrying the operating mechanism 12 and the plungers 13 of which the stems 14 operate through openings 15 in the cover, so that when it is desired to either introduce or remove clothing the operating mechanism may be displaced with the top or cover to expose the entire upper side of the receptacle.

Within the receptacle is arranged a rack 16 preferably of slatted form with the heads 45 17 arranged in parallel spaced relation and supported by end and intermediate cross strips 18 in contact with the surface of the receptacle bottom to permit of circulation of water therethrough and allow for the settling of dirt through the rack to the bottom 50 of the receptacle so as to be removed from the clothes or fabrics resting on the rack. Also preferably the rack is provided with a handle consisting of side uprights 19 and a 55 transverse grip bar 20 which is thus dis-

posed within convenient reach of the top of the receptacle and may be grasped by the operator to remove the rack with the clothes or fabrics from the receptacle to avoid the necessity of independently removing the fabrics by means of a clothes stick or its equivalent, and with the further advantage that when the rack has been raised with the clothes supported thereby it may be turned at an angle to the receptacle and raised on the upper edges thereof to permit of the draining of the excess water from the fabrics prior to removing the latter, or may be supported over a sink or drain for drainage purposes while the contents of the receptacle are emptied and replaced by rinse water or the like.

The plungers consist of disks 21 from which depend rims or flanges 22 forming downwardly opening cups or dishes which come in contact with the fabrics in the receptacles supported by the rack and by reciprocatory movement vertically cause alternate squeezing and suction action which produces a more or less violent circulation of the water and cleansing material through the fabrics to remove foreign matter therefrom.

from. The stems of the plungers are pivotally connected as at 23 with an operating lever 24 forming an element of the operating mechanism and pivotally mounted as at 25 upon a block 26 which is adjustably secured to a standard 27 rising from the lid or cover of the receptacle. Said block is preferably provided with webs or ribs 28 for engagement with seats 29 in the standard and adapted to be locked in place by a cam 30 mounted in the yoke formed by the side arms 31 of the block for contact with the outer surface of the standard. This means of mounting provides for the vertical adjustment of the paths of movement of the plungers to suit the depth of contents or the amount of clothing in the receptacle so that a proper pressure may be applied by the plungers to the clothing with a convenient oscillatory movement of the operating lever. 85 90 95 100

Having described the invention, what is claimed as new and useful is:—

A washing apparatus having a receptacle provided with a removable cover, plungers operating within the receptacle and having their stems extended through openings in said cover and operating mechanism for the 110

plungers mounted upon and carried by the cover and having connection with the stems of said plungers to provide for the displacement of the plungers from the receptacle and the removal of the connected operating mechanism when the cover is detached, said operating mechanism consisting of a lever to which the plunger stems are pivoted, a standard rising from the cover, a bearing block upon which the lever is pivotally mounted and which is adjustable relative to

the standard, and means for locking said bearing block in its adjusted positions, said means consisting of a rib on the bearing block selectively engageable with seats in the standard, and a cam carried by the bearing block for holding said rib in engagement with selected seats. ¹⁵

In testimony whereof he affixes his signature.

CLARENCE L. MORTON.
